UNITED STATES PATENT OFFICE.

ARTHUR T. KUEHNER, OF ELKRIDGE, MARYLAND.

FREIGHT-CAR HOPPER.

1,412,660.

Specification of Letters Patent. Patented Apr. 11, 1923.

Application filed December 24, 1920. Serial No. 432,921.

To all whom it may concern:

Be it known that I, ARTHUR T. KUEHNER, citizen of the United States, residing at Elkridge, in the county of Howard and State of 5 Maryland, have invented certain new and useful Improvements in Freight-Car Hoppers, of which the following is a specification.

This invention relates to an improved 10 hopper for railway freight cars and has as one of its principal objects to provide a hopper which will direct the load as it is discharged away from the track rails and which will be of such construction that repairs 15 may be readily made thereon.

A further object of the invention is to provide a hopper employing a door which will normally remain closed without mechanical pressure thereon.

20 A still further object of the invention is to provide a door so constructed and hung that the door will not become broken or cracked at its margins, thus forestalling the necessity for future cooperage.

25 Another important object of the invention is to provide a door which will remain closed under all working conditions.

A still further object of the invention is to provide a door which may be opened without 30 the necessity for hammering thereon as well as a door having a minimum freezing exposure at the joint between the door and the hopper chute.

35 And the invention has as a still further object to provide a door which, when open, will not hamper the flow of the load through the hopper chute.

Other and incidental objects will appear hereinafter.

40 In the drawings:

Figure 1 is a fragmentary longitudinal sectional view on the line 1—1 of Figure 2, looking in the direction of the arrows, this view showing my improved hopper in connection with a freight car,

45 Figure 2 is a vertical sectional view on the line 2—2 of Figure 1, looking in the direction of the arrows,

50 Figure 3 is a detail elevation showing the locking mechanism employed for locking the doors of the hoppers open and closed,

55 Figure 4 is a fragmentary plan view particularly showing the mounting of the retaining plate employed in connection with each of the doors, and

Figure 5 is a detail perspective view of one of the door guides employed.

Referring now more particularly to the drawings, it will be seen that I have shown my improved hopper in connection with a 60 freight car of conventional design. The side walls of the car are indicated at 10 and extending along said side walls at their bottom edges are the usual angle plates 11. The center sills of the car are indicated at 12 65 and, as will be observed, the car is, as usual, formed medially with confronting pairs of hoppers, the downwardly diverging front walls of which are indicated at 14. The present invention has to do particularly with 70 the type of hopper chute as well as the doors employed and since these features are the same for each pair of hoppers, only one pair of the hoppers will be described in detail.

In carrying the invention into effect, I 75 employ downwardly inclined chutes 15 which are suitably secured to the side walls of the hoppers and to the adjacent wall 14, this latter wall being formed with door openings at the lower ends of the chutes. 80 The chutes are trough shaped, being formed with arcuate bottom portions and, as best shown in Figure 1, gradually increase in depth toward the lower ends thereof. In thus employing arcuate shaped chutes, 85 repairs thereon may be readily made while the chutes will tend to direct the load being discharged therethrough between the track rails. In any construction employing a square shaped chute, the load is discharged 90 in such manner that the material of the load piles upon the rails. However, in the present construction, the curved walls of the chutes tend to direct the material of the load between the rails. Extending about the 95 outer sides of the chutes at their lower ends are angle plates serving to reinforce the chutes at the mouths thereof and arranged in spaced relation to these plates are arcuate retaining plates 17, the outer ends of which 100 are secured to the angle plates 11 while the inner ends of the retaining plates are secured to the center sills 12. As shown in detail in Figure 4, the retaining plates are bolted to the depending flanges of the angle 105 plates 16 and arranged upon the bolts are spacers 18 bearing between said plates. The retaining plates are thus rigidly supported in spaced relation to the plates 16. This construction provides an arrangement where- 110

by water will be prevented from collecting behind the retaining plates while, also, fine material will be prevented from clogging behind the plates at the mouths of the chutes.

5 Secured to the adjacent front wall 14 of the chutes are posts 19 the bases of which abut the center sills 12 and mounted to pivot or swing upon said posts are companion semi-circular doors 20 normally closing the chutes 15 at their lower ends. As best shown in Figure 1, the doors are provided with marginal flanges 21 and secured to said flanges at the upper inner corners of the doors are hinge plates 22 journaled upon said posts. 10 The doors are thus mounted to swing upwardly against the adjacent front wall 14 about the axes of the posts and mounted upon said wall to coact with the free outer margins of the doors are guides 23. As shown in detail 15 in Figure 5, these guides are so formed that the doors are adapted to ride therebeneath so that when the doors are opened, the guides will hold the free outer corners of the doors against outward movement away from the 20 front wall. As shown in Figure 1, the curved portions of the door flanges are notched or cut away so as to ride behind the retaining plates 17. These plates will thus coact with the doors, when the doors 25 are closed, for rigidly supporting the doors against outward movement away from the door openings.

Secured to the body of the car at its sides are bearing brackets 24 and 25 and journaled through said brackets is a cross shaft 26, one end of which is squared. As will be observed, the shaft is spaced in front of the doors and fixed to said shaft are arms 27. Journaled upon the outer end portions 30 of these arms are collars 28 and pivotally connected at their upper ends to said collars are rods 29. Projecting from the doors, near the outer side edges thereof, are posts 30 and journaled upon said posts 35 are collars 31 to which the lower ends of the rods 29 are freely connected. The doors are thus operatively connected with the arms 27. Overlying the bearing 25 and suitably secured to the adjacent side wall of the car 40 is a plate 32 and projecting from said plate are, as particularly shown in Figure 3, stops 33 and 34 respectively. Fixed to the adjacent end portion of the shaft 26 at the outer side of the plate is an arm 35 reduced at its 45 upper end portion to provide shoulders 36 and 37 respectively and pivoted upon the plate above the plane of the upper end of the arm are dogs 38 and 39, these dogs being provided at their free end portions with laterally projecting pins 40 by which the dogs may be readily manipulated.

60 As will now be readily understood in view of the preceding description, the doors 20 normally gravitate to closed position and will not open under any ordinary working

conditions. Possibility of accidental discharge of the load is thus eliminated. As shown in Figure 3, when the doors are closed, the arm 35 upon the shaft 26 will move into engagement with the stop 33. 70 The dog 38 may then be swung to coact with the shoulder 36 of the arm for locking the doors closed. However, as will be perceived, no mechanical pressure is employed, nor is any required, to normally 75 maintain the doors closed, the doors being held closed by gravity and, of course, pressure of the load against the doors will also operate to bind the doors in closed position. By applying a suitable lever to the 80 squared end of the shaft 26 and rotating the shaft counter-clockwise, the arms 27 will be swung upwardly so that the doors will be simultaneously opened. Opening movement of the doors will be limited by 85 the engagement of the arm 35 with the stop 34. The dog 39 may then be engaged with the shoulder 37 of said arm for locking the doors open. In this connection it is to be noted that due to the substantially semi-circular shape of the doors, a minimum freezing exposure is incurred at the joint between the doors and the retaining plates 17 and since provision is made whereby water will drain behind the plates, as previously 90 explained, the doors will not, under ordinary circumstances, be frozen shut. Therefore, 95 it will not be necessary, as is often the case with hopper doors as now constructed, to hammer upon the doors in order that the 100 doors may be opened. After the doors have been so opened, it will be seen that the flow of the load through the chutes will be unhampered so that the load will readily discharge through said chutes. 105

Having thus described the invention, what is claimed as new is:

1. A car hopper including a chute, a retaining plate carried thereby but spaced from the chute to provide an opening between the plate and chute through which material may fall, and a pivoted sliding door normally closing the chute engaging behind said plate coacting therewith. 110

2. A car hopper including a chute, a pivoted sliding door normally closing the chute, a shaft, an arm fixed to the shaft, a collar swiveled upon the arm, a post projecting from the door, a collar swiveled upon said post, and a rod connecting said collars and 120 pivotally connected thereto whereby the shaft may be rocked for shifting the door to open position.

3. A car hopper including a chute, a pivoted sliding door normally closing the chute, a shaft, an operative connection between the shaft and the door whereby the shaft may be rocked for slidably swinging the door to open position, an arm fixed to the shaft, means arranged to coact with said arm at 130

one side thereof for locking the door open, and means arranged to coact with the arm at its opposite side for locking the door closed.

4. A car hopper including a chute, a pivoted sliding door normally closing the chute, a shaft, an operative connection between the shaft and the door whereby the shaft may be rocked for slidably swinging the door to open position, an arm fixed to the shaft, and 10 companion dogs one arranged to coact with said arm at one side thereof for locking the door open, and the other arranged to coact with the arm at its opposite side for locking the door closed.
5. A car hopper including a chute provided at its lower end with a discharge opening, and a pivoted door mounted at the

lower end of said chute to travel in a single plane and slidably upwardly across said opening swinging about the pivotal center 20 of the door.

6. In a car, the combination of a hopper having an inclined trough shaped chute extending longitudinally of the car and provided at its lower end with a discharge opening, and a substantially semi-circular door pivoted near one corner thereof to travel in a single plane at the lower end of said chute and slidably upwardly across said opening swinging about the pivotal center 25 30 of the door.

In testimony whereof I affix my signature

ARTHUR T. KUEHNER. [L.S.]
